UNITED STATES PATENT OFFICE

HERALD B. GREENING, OF HAMILTON, ONTARIO, CANADA, AND JAMES W. GALLOWAY, OF DETROIT, MICHIGAN, ASSIGNEES TO GALLOWAY ENGINEERING COMPANY, LIMITED, OF HAMILTON, ONTARIO, CANADA

CYLINDER CONSTRUCTION FOR TWO-CYCLE INTERNAL-COMBUSTION ENGINES

Application filed November 23, 1928. Serial No. 321,356.

The principal objects of this invention are to produce cylinders of the type in which two separate cylinders are joined by a head which forms a common combustion space in 5 which the weight will be reduced to the minimum and will be suitable for aeroplane engine construction.

The principal features of the invention consist in the forming of the cylinders separately, then welding them together in such a manner as to provide adequate seal for the common cylinder head which forms a common combustion chamber for the two cylinders.

15 In the drawings, Figure 1 is a plan view of the top of the cylinder head partly broken away and showing the top end of the united cylinders.

Figure 2 is a vertical mid-sectional view 20 through the line 2—2 of Figure 1.

In the construction of aeroplane engines it has been the practice to forge the cylinders and then machine the metal down to the minimum required thickness.

25 The cylinders A and B, the top ends of which are shown herein, are constructed in the above manner. The top flanges *a* and *b* respectively and the radiating ribs *c* are flattened on a short chord X and the flattened 30 edges are butted together and welded, thus joining the two cylinders securely together in parallel alignment.

V-shaped blocks D of the same thickness 35 of the flanges *a* and *b* are fitted in between the converging edges of the said flanges where they are secured together in the weld and the meeting edges of the blocks D and the cylinder flanges are welded along the line *d*. These 40 blocks extend the flange surfaces well beyond the bore of the cylinders and form with the cylinder flanges a continuous sealing surface extending around the pair of cylinders.

The cylinder head E may be of cast metal 45 and it is constructed of a substantially elliptical shape, having a flange *e* to rest upon the flanges *a* and *b*, the side portions extending across the juncture of the two cylinders extending over the welded-in blocks D. This 50 construction obviates any constriction of the

chamber in the head between the pair of cylinders.

The central raised portion F of the head E is of arched formation extending from points inside the outer cylinder walls *a'* and *b'* and the volumetric capacity of the chamber enclosed within the head above the tops of the cylinders is figured in accordance with the diameter and displacement of the cylinders so that when the pistons operating in 60 the cylinders move to the top of the cylinders, the chamber will contain an explosive mixture of the required pressure.

It will be noted that the longitudinal arch of the cylinder heads terminates well inside 65 the cylinder walls *a'* and *b'* so as to direct the flow of carburetted air from one cylinder to the other in such a manner as to cause a very definite downward flow into one of the cylinders, which of course will be the cylinder 70 having the exhaust port therein and the result is extensive turbulence.

The joining of the two cylinders together in the manner described enables the use of the light construction of cylinder with a long 75 elliptical cap while retaining the lightest possible weight of materials and a perfectly tight joint between the cylinder head and cylinders will be obtained.

The whole structure is extremely rigid and 80 strong.

What we claim as our invention is:—

1. A cylinder construction, comprising a pair of forged and machined cylinders having their head flanges welded together, closure blocks fitting between the converging edges of said head flanges and flush with the top surface thereof and welded to said flanges to form a reinforcing bridge therebetween, and a cylinder head having an arched portion connecting both cylinders and a flange adapted to engage the flush surfaces of the flanges of the cylinders and the inserted connecting bridge blocks thereof.

2. A cylinder construction, comprising a pair of flanged cylinders arranged in parallel relation to each other having their head flanges flattened on one side abutting and welded together, a pair of V-shaped blocks inserted between and engaging the meeting 100

peripheries of said flanges and welded thereto, a cylinder head having a wide flange extending inwardly beyond the head flanges of the cylinders, and an arched recess in the underside connecting the two cylinders in a common combustion chamber.

3. A cylinder construction, comprising a pair of cylinders each having flanged heads and cooling fins below the head flanges, said cylinders having their head flanges and cooling fins flattened on one side and abutting in a common plane, and metallic fillets welded in the converging space between said head flanges and forming a reinforcing connection therebetween.

4. An internal combustion engine cylinder construction, comprising a pair of flanged cylinders arranged side by side with their head flanges disposed in a common plane, fillet blocks inserted between said head flanges and permanently welded thereto, and a combustion head closing the head end of said cylinders and connecting their interiors.

5. An internal combustion engine cylinder construction, comprising a pair of cylinders parallelly arranged and having turned head flanges permanently secured together in a welded joint and forming a continuous head flange the minimum width of which is greater than the average bore of said cylinders, and a cylinder head spanning the ends of the two connected cylinders and sealed against said continuous cylinder flange, said head being arched to form a common combustion chamber for said cylinders.
